UNITED STATES PATENT OFFICE

115,142

DESIGN FOR A GRILL

John Bergholm, Chicago, Ill.

Application March 3, 1939, Serial No. 83,316

Term of patent 3½ years

To all whom it may concern:

Be it known that I, John Bergholm, a citizen of the United States, residing at Chicago, in the county of Cook and State of Illinois, have invented a new, original, and ornamental Design for a Grill, of which the following is a specification, reference being had to the accompanying drawing, forming part thereof.

embodying my new design.

I claim:

The ornamental design for a grill, substantially as shown.

JOHN BERGHELM.
